VACUUM PUMP

James P. Johnson, Shaker Heights, Ohio

Application April 24, 1934, Serial No. 722,155

14 Claims. (Cl. 230—153)

This invention relates to a rotary pump of the vane or blade type in which the rotor is eccentrically mounted with respect to the chamber within which it rotates and has for its primary object to provide an improved pump of this type which is simple in construction, efficient in operation, and inexpensive to manufacture.

A further object of the invention is to provide a pump of the type referred to adapted to create a vacuum or reduced pressure with respect to atmosphere and especially designed for use on aircraft for creating the necessary pressure required in the operation of various instruments and gauges.

A still further object of the invention is to provide a means for controlling and varying the amount of pressure created by the operation of the pump.

Another object of the invention resides in providing a pump of the type referred to which is capable of being operated in opposite directions with equal efficiency and without the necessity of disengaging or dismantling the pump.

A still further object of the invention is to provide a pump of the type referred to which is light in structure, has the required capacity and which will efficiently operate under all conditions of flying.

A still further object of the invention is to provide a novel means for lubricating the movable parts of a pump of the type referred to.

With the objects above indicated and other objects hereinafter explained in view, the invention consists in the construction and combination of elements hereinafter described and claimed.

Referring to the drawings:

Figure 1 is a top plan view of a full sized pump embodying the present invention.

Fig. 2 is a longitudinal sectional view taken on line 2—2 of Fig. 3.

Fig. 3 is a transverse sectional view taken on line 3—3 of Fig. 2.

Fig. 4 is a transverse sectional view taken on line 4—4 of Fig. 1.

Fig. 5 is a top plan view of the valve member shown in Fig. 4.

Fig. 6 is an end view of the lubricating side.

Fig. 7 is an end view of the driven side.

Fig. 8 is a transverse sectional view of a modified form of rotor and blades.

In the drawings a full sized pump is illustrated which has been designed especially for use in aircraft and is of the vacuum or reduced pressure type employed in connection with the operation

of various types of instruments and gauges required in connection with flying. In the first place the weight of the pump and the overall dimensions are of primary importance, because the weight of the plane must be kept as low as possible with respect to the horse power of the motor, in order to obtain the best flying conditions. Pumps for this type of use are required to operate at one and one half times engine speed and are actually tested at speeds up to 10,000 R. P. M. Therefore, the metals of the relatively movable parts of the pump must be light and of such characteristics to prevent seizing and undue wear caused by friction. The structure of the pump and the metals employed in the various elements are therefore of primary importance in providing a pump of high efficiency and still coming within the requirements set forth.

Referring particularly to Figs. 1, 2, and 3, 10 indicates generally a housing, preferably of aluminum or some similar light weight material, which is open at one end and closed at the opposite end. At the closed end of the housing 10 an axial extension 11 is provided, preferably formed integral with the housing, and at the free end of said extension there is a laterally extending flange 12, more clearly shown in Fig. 7, having openings 13 provided therein by which the housing may be suitably attached to a portion of the plane. The housing 10 is provided with a circular bore 14 extending inwardly from the open end of the housing and a cover plate 15 is detachably connected to the housing adjacent the open end by means of bolts 16, more clearly shown in Fig. 6. This cover plate 15 not only serves the purpose of closing the open end of the housing 10, but additionally functions as one of the end walls of the circular opening 14.

A tubular sleeve 17, preferably of hard cast iron, is secured within the circular opening 14 of the housing and has its inner end abutting the closed end of the housing, while the opposite end is engaged by the cover plate 15, as clearly shown in Fig. 2. The housing 10 is provided with passageways 18 and 19 of identical area disposed on diametrically opposite sides of the housing and normally non-communicating. The sleeve 17 is provided with spaced transverse openings 20 and 21 communicating with the passageway 18 at its opposite extremities, while spaced transverse openings 22 and 23 are provided in the sleeve 17 and communicating with the passageway 19 at its opposite extremities, as clearly shown in Fig. 3. These pairs of openings are provided in the sleeve 17 so that the pump may

be operated in opposite directions without requiring any readjustment of the operating parts. At the upper portion of the housing 10 screw-threaded openings 24 and 25 are provided which 5 communicate with the upper portions of the passageways 18 and 19, respectively, to permit the pump to be properly connected with the various instruments in a manner well understood.

A rotor 26, preferably made of hardened steel 10 is eccentrically positioned within the sleeve 17 and has a running engagement with the inner surface of the sleeve 17 at 27. The rotor, of course, is coextensive with the sleeve 17, as shown in Fig. 2. One end of the rotor 26 is provided 15 with an axial extension 28, preferably formed integral therewith and which is antifrictionally mounted in a ball bearing race 29 contained in the extension 11 of the housing, as clearly shown in Fig. 2. The opposite end of the rotor 26 is 20 provided with an axial extension 30, preferably formed integral therewith, and likewise is antifrictionally mounted in a ball bearing race 31 contained in a recessed portion 32 provided on the inner side of the cover plate 15. The extension 30 is provided with an axial opening 33, which communicates with an axial bore 34 of larger diameter provided in the rotor 26 for a purpose to be later described, the longitudinal length of the bore, however, being slightly less 30 than the longitudinal length of the rotor 26.

The rotor 26 is provided with a plurality of radially disposed slots 35 which extend through the wall of the rotor and throughout its length, there being in this particular construction four 35 of such slots employed, although various numbers may be employed, depending upon the nature of the pump. The relationship between the length of the bore 34 and the length of the rotor 26 permits the segments of the rotor between the slots 35 to be integrally united with the extensions 28 and 30, respectively, at opposite ends so as to prevent any tendency for these segments to move outwardly by centrifugal action when the rotor is rotated at high speeds.

Blades 36, preferably of heat-treated aluminum alloy, are disposed in the slots 35 and have a sliding fit therein. These blades are substantially T-shaped in longitudinal section and have their outer ends formed arcuate at 37, as shown in Fig. 3, the outer ends being adapted to engage the inner peripheral surface of the sleeve 17 due to centrifugal action as the rotor is rotated. The inner ends 38 of the blades 36 are also formed arcuate and engage with a hollow roller member 39 disposed within the bore 34 of the rotor 26. The opening 33 in the extension 30 of the rotor is made of sufficient diameter to permit the roller member 39 to be inserted therethrough so as to properly position the roller member in the bore 34 and, due to the fact that the diameter of the bore 34 is larger than the diameter of the opening 33, the roller member 39 is prevented from accidental displacement and any appreciable amount of longitudinal movement within the bore, at the same time permitting ready access in case it becomes necessary to replace the roller member.

The rotor 26 is provided with longitudinally extending openings 40 in the wall thereof between the slots 35 for the purpose of lightening as much as possible the weight of the rotor. Likewise, the blades 36 are provided with a plurality of longitudinally extending openings 41 for the similar purpose of lightening the weight thereof.

While the blades 36 are made of an aluminum alloy, principally because of its lightness, it is necessary to lighten the blades to a further extent, which is accomplished, in the present construction, by the provision of the openings 41. 5 It should be noted that there is nothing which holds the blades against outward movement as the rotor rotates and, consequently, the weight of the blades becomes quite a factor by reason of the outward pressure of the blades upon the 10 sleeve.

It is necessary to provide suitable lubrication for the relatively movable parts of the pump and, in the present instance, this is accomplished by providing a tubular member 42 having one end 15 secured in an opening 43 provided upon the inner face of the cover plate 15, the free end extending into the interior of the roller member 39. An opening 44 communicates with the opening 43 in the cover plate and extends upwardly communicating with a screw-threaded opening 45. This screw-threaded opening may be connected with any suitable source of oil supply available. The hollow roller member 39 is provided with a plurality of openings 46 extending through the 25 wall thereof so that when the lubricant is discharged from the tubular member 42 it will be deposited in the interior of the roller member. Upon rotation of the rotor when the pump is in operation, centrifugal action will cause the lubricant to flow outwardly between the relatively movable parts and the lubricant may then be carried off through one of the screw-threaded openings 24 or 25, depending upon the direction of rotation of the motor, to the housing of the 30 motor.

The free end of the extension 28 on the rotor 26 has a bushing 47 secured to the outside thereof which is rotatably mounted in an opening 48 provided in the end of the extension 11. A packing ring 49 is disposed in a groove provided in the extension and engages the bushing 47 to prevent the passage of oil thereby. The end of the extension 28 has an axial bore 50 within which is disposed an extension 51 of a T-shaped 45 member 52. Aligned openings are provided through the bushing 47, extension 28, and extension 51 to receive a pin 53 which securely maintains these elements in assembled relation. The T-shaped member 52 is adapted to be connected 50 with the motor of the airplane or other suitable means for imparting rotation to the rotor.

As the pump is designed principally to create a reduced pressure and being of the reversible type, it is desirable to provide a suitable means 55 which may be adjusted to vary the amount of pressure produced. In Fig. 4 a preferred construction is illustrated wherein this control means is formed as an integral part of the housing 10. This consists of an extension 54 provided at the 60 upper portion of the housing adjacent the inlet and outlet openings 24 and 25. The extension is provided with a pair of axially aligned bores 55 and 56 extending inwardly from the opposite ends of the extension and spaced apart to provide a 65 transverse partition 57 substantially midway of the length of the extension. These bores 55 and 56 are normally non-communicative and the bore 55 communicates with the passageway 18 through a slotted opening 58, while the bore 56 communicates with the passageway 19 through a slotted opening 59. The bores 55 and 56 are, therefore, in communication with the screw-threaded openings 24 and 25 connected to the instruments to be operated.

With the rotor 26 operating in a clockwise direction the valve mechanism for controlling the amount of air drawn into the pump is contained in the extension 54 adjacent the bore 55. Slidably and loosely mounted in the outer end of the bore 55 is a valve member 60 of non-metallic material and a material which is light in weight. Slots 61 are provided in the peripheral edge of the valve member, as shown in Fig. 5 to permit ready and rapid passage of the air when the valve is open. A cap 62 is detachably connected to the end of the extension by means of bolts 63 and is provided with an axial opening 64 through which air may be drawn from the surrounding atmosphere. A valve seat 65 is provided on the inner surfaces of the cap 62 and extends around the opening, the valve member 60 normally cooperating with the valve seat to control the amount of air drawn thereby. The partition 57 has an axially extending interiorly screw-threaded opening 66 provided therein and a member 67 has an exteriorly screw-threaded portion 68 adjustably disposed in the screw-threaded opening 66. The member 67 is provided with an axial bore 69 extending inwardly from the end adjacent the valve member 60 which receives a coiled spring 70, one end of which abuts the base of the bore, while the other end extends beyond the end of the member 67 and into engagement with the under side of the valve member 60 to normally urge the valve member 60 into engagement with the valve seat 65. A screen 71 is secured to the cap 62 and extends over the opening 64 so as to prevent objectionable particles from passing therethrough into the pump, which would otherwise interfere with the operation. The opposite end of the member 67 has an enlarged head portion 72 provided with a transverse slot 73. Adjacent this end of the extension 54 a cap 74 is provided which is also detachably connected to the open end of the extension by means of bolts 75. The cap 74 has a depending extension or tongue 76, preferably formed integral with its inner side and which is disposed in the slot 73. By removing the bolts 75 the member 67 may be adjusted longitudinally within the screw-threaded opening by turning the cap 74, and the openings to receive the bolts 75 may be placed in any desired spaced relation so as to obtain the desired adjustment.

In the event that the rotor 26 should be rotated in a counter-clockwise direction the only change necessary to render the pump operable is to reverse the valve mechanism. By that is meant the cap 62, the valve 60, the member 67, and the spring 70 are removed, as well as the cap 74 upon the opposite end of the extension. This entire structure then is reversed so that the valve operating means is mounted on the opposite end of the extension from that shown in Fig. 4, with the valve member 60 slidably disposed in the bore 55.

In Fig. 8 a modified form of rotor is shown which may be substituted in place of the rotor 26 shown in the other figures of the drawings, but it should be understood that the other parts of the pump structure remain the same and operate in the same manner.

It may be desirable to provide a pump structure in which there is practically no chance for any foreign matter accumulating between the rotor and that portion of the liner with which it usually has a running fit such as at 27 in Fig. 3.

A proposed arrangement consists in providing a liner 80 of the same type and character as the liner 17. A rotor 81 is eccentrically positioned in the liner 80, but a much greater clearance is

maintained between these members, in fact not a running fit. The rotor 81 has radially disposed slots 82 extending longitudinally through the wall thereof and communicating with an axial bore 83 provided in the rotor. The rotor also has a plurality of openings 85 spaced apart and extending longitudinally between the slots 82 to lighten the structure. Blades 86 are slidably disposed in the slots 82 and are provided with laterally extending outer end portions 87 formed integral. The outer surface of the end portions 87 are formed arcuate and, due to the increased width a much more effective surface is provided which results in less wear and longer life.

The outer end portions 87 are adapted to contact with the inner surface of the liner 80 as the rotor is rotated. Portions of the rotor adjacent the outer end portions 87 are flattened as indicated at 88.

A hollow roller member 89 is disposed in the bore 83 of the rotor and engages the inner ends of the blades 86 to maintain them in spaced relation. The inlet and outlet openings 90 provided in the liner 80 should be positioned so that there is no communication between the openings irrespective of the positions of the blades 86.

In the operation of the pump assuming the rotor 26 to be rotated in a clockwise direction, as shown in Fig. 3, the opening 24 is connected by a conduit with the various instruments to be operated, while the opening 25 is connected by a suitable conduit preferably with the interior of the motor housing. The instruments, of course, are connected with atmosphere in the usual manner and the interior of the pump is likewise connected with atmosphere through the valve control means when said means is open. As the pump is rotated a suction is created by reason of the blades 36 which removes the valve 60 from its seat 65 when such suction exceeds the tension of the spring 70, the amount of movement or opening thereof being dependent upon the pressure exerted by the spring 70. Such action creates a vacuum in the conduit leading to the instruments as the blades 36 tend to draw from the passageway 18 and discharge the air under pressure through the opening 25. The amount of vacuum created for the operation of the instruments should remain as nearly constant as possible throughout a wide range of engine speed. The accuracy of the instruments depends upon this amount of vacuum being as nearly constant as possible and for this reason the valve member 60 is made of non-metallic material. The valve member, being of light weight, is therefore unaffected whether the plane is flying upside down, banking around to the right or left, or flying right-side up. The pump has been designed and built to operate under constant conditions, irrespective of the changes in atmospheric pressure or the speeds of the plane.

While I have described the preferred embodiment of the invention, it is to be understood that I am not to be limited thereto inasmuch as changes and modifications may be resorted to without departing from the spirit of the invention as defined in the appended claims.

Having thus described my invention, I claim:

1. A vacuum pump comprising a housing having a circular chamber therein open at one end, said housing being further provided with inlet and outlet passageways communicating with said chamber adapting the pump for operation in opposite directions, a tubular liner secured to the peripheral wall of said chamber and having open-

ings therethrough communicating with said inlet and outlet openings, a cover plate detachably connected to said housing and adapted to close the open end of said chamber, a rotor eccentrically positioned in said chamber and having a running engagement with the inner peripheral wall of said liner between said inlet and outlet passageways, extensions on said rotor rotatably mounted anti-frictionally in said housing and cover plate respectively, one of said extensions having an axial opening communicating with an axial bore of larger diameter provided in said rotor, the other of said extensions projecting through said housing and adapted for connection with a driving means, said rotor being further provided with a plurality of radially disposed slots extending through the wall thereof, blades slidably mounted in said slots and having their outer ends in running engagement with the inner peripheral wall of said liner, and a roller member insertable through the opening in said extension and disposed in the bore in said rotor, said roller member being normally maintained within the bore by engagement with the adjacent end walls of said rotor bore and engageable with the inner ends of said blades to maintain the latter in spaced relation.

2. A vacuum pump comprising a housing having a circular chamber therein open at one end, said housing being further provided with inlet and outlet passageways communicating with said chamber adapting the pump for operation in opposite directions, a liner on the peripheral wall of said chamber having openings therethrough communicating with said inlet and outlet passageways, a cover plate detachably connected to said housing and adapted to close the open end of said chamber, a rotor eccentrically positioned in said chamber and having a running engagement with the inner peripheral wall of said liner between said inlet and outlet passageways, extensions on said rotor rotatably mounted anti-frictionally in said housing and cover plate respectively, one of said extensions having an axial opening communicating with an axial bore of larger diameter provided in said rotor, the other of said extensions projecting through said housing and adapted for connection with a driving means, said rotor being further provided with a plurality of radially disposed slots extending through the wall thereof, blades slidably mounted in said slots and having their outer ends in running engagement with the inner peripheral wall of said liner, and a roller member insertable through the opening in said extension and disposed in the bore in said rotor, said roller member being normally maintained within the bore by engagement with the adjacent end walls of said rotor bore and engageable with the inner ends of said blades to maintain the latter in spaced relation.

3. A vacuum pump comprising a housing having a circular chamber therein open at one end, said housing being further provided with inlet and outlet passageways communicating with said chamber adapting the pump for operation in opposite directions, a tubular liner secured to the peripheral wall of said chamber and having openings therethrough communicating with said inlet and outlet passageways, a cover plate detachably connected to said housing and adapted to close the open end of said chamber, a rotor eccentrically positioned in said chamber and having a running engagement with the inner peripheral wall of said liner between said inlet

and outlet passageways, extensions on said rotor rotatably mounted anti-frictionally in said housing and cover plate respectively, one of said extensions having an axial opening communicating with an axial bore of larger diameter provided in said rotor, the other of said extensions projecting through said housing and adapted for connection with a driving means, said rotor being further provided with a plurality of radially disposed slots extending through the wall thereof, blades slidably mounted in said slots and having their outer ends in running engagement with the inner peripheral wall of said liner, a hollow roller member insertable through the opening in said extension and disposed in the bore in said rotor, said roller member having an opening through the wall thereof and being normally maintained within the bore by engagement with the adjacent end walls of said rotor bore and engageable with the inner ends of said blades to maintain the latter in spaced relation, and means provided in said housing for conveying a lubricant to the interior of said hollow roller member.

4. A vacuum pump comprising a housing having a circular chamber therein open at one end, said housing being further provided with inlet and outlet passageways communicating with said chamber adapting the pump for operation in opposite directions, a tubular liner secured to the peripheral wall of said chamber and having openings therethrough communicating with said inlet and outlet passageways, a cover plate detachably connected to said housing and adapted to close the open end of said chamber, a rotor eccentrically positioned in said chamber and having a running engagement with the inner peripheral wall of said liner between said inlet and outlet passageways, extensions on said rotor rotatably mounted anti-frictionally in said housing and cover plate respectively, one of said extensions having an axial opening communicating with an axial bore of larger diameter provided in said rotor, the other of said extensions projecting through said housing and adapted for connection with a driving means, said rotor being further provided with a plurality of radially disposed slots extending through the wall thereof and a plurality of longitudinally extending openings positioned between and substantially parallel with said slots, blades slidably mounted in said slots and having their outer ends in running engagement with the inner peripheral wall of said liner, and a roller member insertable through the opening in said extension and disposed in the bore in said rotor, said roller member being normally maintained within the bore by engagement with the adjacent end walls of said rotor bore and engageable with the inner ends of said blades to maintain the latter in spaced relation.

5. A vacuum pump comprising a housing having a circular chamber therein open at one end, said housing being further provided with inlet and outlet passageways communicating with said chamber adapting the pump for operation in opposite directions, a tubular liner secured to the peripheral wall of said chamber and having openings therethrough communicating with said inlet and outlet passageways, a cover plate detachably connected to said housing and adapted to close the open end of said chamber, a rotor eccentrically positioned in said chamber and having a running engagement with the inner peripheral wall of said liner between said inlet and outlet passageways, extensions on said rotor rotatably mounted anti-frictionally in said hous-

cover plate respectively, one of said extensions having an axial opening therethrough communicating with the bore in said rotor but of smaller relative diameter, the other of said extensions 5 projecting through the adjacent wall of said housing and adapted for connection with a driving means, said rotor being further provided with a plurality of radially disposed slots extending through the wall thereof, blades slidably mounted 10 in said slots and having their outer ends in running engagement with the inner peripheral wall of said liner and their inner ends projecting into the bore in said rotor, and a hollow roller member disposed within the bore in said rotor and engageable 15 with the inner ends of said blades to maintain the latter in spaced relation, said roller member being insertable through the opening in one of said extensions and normally maintained within the bore by engagement with the adjacent end walls of the latter.

10. A vacuum pump comprising a housing having a circular chamber therein open at one end, said housing being further provided with inlet 30 and outlet passageways communicating with said chamber, a tubular liner secured to the peripheral wall of said chamber and having openings therethrough communicating with said passageways, a cover plate detachably connected to said housing and adapted to close the open end of said chamber, a rotor eccentrically positioned in said chamber and having a running engagement with the inner peripheral wall of said liner between said passageways, said rotor having an 35 axial bore and walls at the opposite ends of said bore, said rotor being further provided with a plurality of radially disposed slots extending through the outer wall thereof, axial extensions on said rotor rotatably mounted in said housing 40 and said cover plate respectively, one of said extensions having an axial opening therethrough communicating with the bore in said rotor but of a smaller relative diameter, the other of said extensions projecting through the adjacent wall 45 of said housing and adapted for connection with a driving means, blades slidably mounted in said slots and having their outer ends of substantially the same length as the length of said rotor and their inner ends of substantially the same length 50 as the length of said bore and disposed in the latter, and a roller member disposed within the bore in said rotor and engageable with the inner ends of said blades to maintain the latter in spaced relation, said roller member being 55 insertable through the opening in one of said extensions and normally maintained within the bore by engagement with the adjacent end walls of the latter.

11. In a rotary pump structure, a rotor having an axial bore and walls at the opposite ends thereof, said rotor being further provided with a plurality of radially disposed slots extending through the outer wall thereof, axial extensions on the opposite ends of said rotor by which the latter is 60 rotatably mounted, one of said extensions having an axial opening therethrough communicating with the interior of said bore but of smaller relative diameter, blades slidably mounted in said slots and having their inner ends projecting into the bore in said rotor, and a roller member dis-

posed within the bore in said rotor and engageable with the inner ends of said blades to maintain the latter in spaced relation, said roller member being insertable through the opening in one of said extensions and normally maintained within the bore by engagement with the adjacent end walls of the latter.

12. A vacuum pump comprising a housing having a circular chamber therein and provided with inlet and outlet passageways communicating with said chamber, a rotor eccentrically positioned in said chamber and having a running engagement with the inner peripheral wall of the latter between said inlet and outlet passageways, extensions on said rotor rotatably mounted in said 15 housing, one of said extensions having an axial opening communicating with an axial bore of larger diameter provided in said rotor, the other of said extensions projecting through said housing and adapted for connection with a driving 20 means, said rotor being further provided with a plurality of radially disposed slots extending through the wall thereof, blades slidably mounted in said slots and having their outer ends in running engagement with the inner peripheral wall 25 of said chamber, and a roller member insertable through the opening in said extension and disposed in the bore in said rotor, said roller member being normally maintained within the bore by engagement with the adjacent end walls and engageable with the inner ends of said blades to maintain the latter in spaced relation.

13. A vacuum pump comprising a housing having a circular chamber therein and provided with inlet and outlet passageways communicating with said chamber, a rotor eccentrically positioned in said chamber and having a running engagement with the inner peripheral wall of the latter between said inlet and outlet passageways, extensions on said rotor rotatably mounted in said 35 housing, one of said extensions having an axial opening communicating with an axial bore of larger diameter provided in said rotor, the other of said extensions projecting through said housing and adapted for connection with a driving means, 40 said rotor being further provided with a plurality of radially disposed slots extending through the wall thereof, blades slidably mounted in said slots and having their outer ends in running engagement with the inner peripheral wall of said chamber, a hollow roller member insertable through the opening in said extension and disposed in the bore in said rotor, said roller member being normally maintained within the bore by engagement with the adjacent end walls and engageable with the inner ends of said blades to maintain the latter in spaced relation, said housing being provided with a lubricant passageway, and a tubular extension on said housing and having one end communicating with said lubricant passageway 50 and its other end freely projecting into said hollow roller member the latter provided with a plurality of openings extending through the wall thereof.

14. A vacuum pump comprising a cast housing 65 having a circular chamber extending inwardly thereof to provide an open end, said housing having passageways of substantially identical area disposed upon diametrically opposite sides and extending part way around said chamber, the upper 70 ends of said passageways being terminated by a transverse partition, said housing having inlet and outlet openings, one positioned on each side of said partition and communicating with the respective passageway, a tubular sleeve insertable in said 75

circular chamber and secured therein against relative rotation, said sleeve being in length substantially the depth of said chamber and having pairs of openings therethrough communicating with the respective passageways, the openings of each pair being positioned adjacent the extremities of the respective passageways, a cover plate detachably connected to said housing and adapted to close the open end of said chamber, 5 said cover plate having a portion engageable with the adjacent end of said sleeve to retain the latter within said chamber, a rotor eccentrically positioned in said sleeve and having a running engagement with the inner peripheral wall of the latter adjacent said partition, said rotor being 10 adapted for rotation in either direction, axial extensions on the opposite ends of said rotor rotatably mounted in said housing and cover plate respectively, one of said extensions having an

axial opening therethrough communicating with an axial bore of relatively larger diameter provided in said rotor, the other of said extensions projecting through the adjacent wall of said housing and adapted for connection with a driving means, said rotor being further provided with a plurality of radially disposed slots extending through the wall thereof, blades slidably mounted in said slots and having their outer ends in running engagement with the inner peripheral wall 15 of said sleeve, and a roller member insertable through the axial opening in one of said extensions and disposed in the bore in said rotor, said roller member being normally maintained within said bore by engagement with the adjacent end walls and engageable with the inner ends of said blades to maintain the latter in spaced relation.

JAMES P. JOHNSON.
